CLAIM

The ornamental design for a bicycle tire repair tool, as shown and described.

DESCRIPTION

FIG. 1 is a front view of a bicycle tire repair tool showing my new design, having cap and barrel assembled;

FIG. 2 is a right hand side view thereof;

FIG. 3 is a rear view thereof;

FIG. 4 is a left hand side view thereof;

FIG. 5 is a perspective view of the tool, exploded;

FIG. 6 is a bottom view of the cap with the barrel removed;

FIG. 7 is a side view of FIG. 6; and,

FIG. 8 is a top view of the barrel with the cap removed.

FIG. 1

FIG. 2

FIG. 3

FIG. 4

FIG. 5

FIG. 6

FIG. 7

FIG. 8
